FIG. 1.

FIG. 2.

FIG. 4.

FIG. 6.

Inventor

DOUGLAS COLLINS

Chas. K. Davis:

Attorney

Patented Sept. 15, 1925.

1,553,987

UNITED STATES PATENT OFFICE.

DOUGLAS COLLINS, OF SALISBURY, NORTH CAROLINA.

CIGARETTE HOLDER.

Application filed July 10, 1924. Serial No. 725,149.

To all whom it may concern:

Be it known that I, DOUGLAS COLLINS, a citizen of the United States, residing at Salisbury, in the county of Rowan and State 5 of North Carolina, have invented certain new and useful Improvements in Cigarette Holders, of which the following is a specification.

10 My present invention relates to improvements in cigarette holders of the type wherein an attachment is utilized for retaining and for ejecting the cigarette as required. The primary object of my invention is the provision of a device of this character that 15 is applicable for use in connection with standard cigarette holders which will positively retain the cigarette in the holder for the smoker's use; by means of which the butt end of the consumed cigarette may with 20 facility be ejected from the holder; and also providing means for cleansing the smoke duct in the holder. In accomplishing these objects I utilize an attachment which is comparatively inexpensive in the cost of production, 25 is simple in construction and operation, and which enhances the appearance and utility of the cigarette holder with which it is used.

30 The invention consists in certain novel combinations and arrangements of parts in a device of this nature as will hereinafter be more fully set forth and claimed.

35 In the accompanying drawings I have
illustrated one complete example and a modi-
fication of the physical embodiment of my
invention, wherein the parts are combined
and arranged, first as a combined retainer
and ejector, and second as a combined re-
tainer, ejector and cleanser, according to the
40 best modes I have thus far devised for the
practical application of the principles of my
invention.

45 Figure 1 is a view in side elevation showing a cigarette and cigarette holder in dotted lines with the attachment of my invention in operative position to retain the cigarette in the holder.

Figure 2 is a view similar to Figure 1 but with the device in ejecting position, which also is the loading or filling position for the holder.

Figure 3 is a perspective view of the combined retainer and ejector of the two preceding figures of drawing.

Figure 4 is a perspective view of a modified device which combines with the device of Figure 3 a cleanser for the holder. 55

Figure 5 is a view in side elevation similar to Figure 1 with the attachment of Fig. 4 in operative position.

Figure 6 is a view similar to Figure 2 with the device in ejecting position.

The device of the invention is capable of use with all standard and conventional styles or types of cigarette holders, one form of such holder being indicated by dotted lines as 1 in the drawings. The holder may be of amber or other suitable material and is fashioned with the usual socket head 2 for the reception of the cigarette C also shown in dotted lines, and the usual smoke duct 3 extends from the socket head through the holder to the mouth piece 4, which latter has a conventional form of head 5 at its end. 65 70

In the form of the invention illustrated in Figures 1, 2 and 3 the device or attachment is a combined retainer and ejector, preferably made up of resilient metal, and finished to provide an ornamental feature for the cigarette holder. 75 80

Preferably the device is fashioned from a single piece of metal by the use of suitable dies or a stamping machine, and comprises a head 6 of the required shape and dimensions for insertion into the end of a cigarette. At its rear end the head is provided with a bend 7 and an arm 8 projects forwardly from the bend. At the front of the device a second bend 9 is fashioned which joins the arms 8 with an integral clip 10. The clip 10 is 85
slidable on the exterior of the holder and is provided with a pair of friction arms 11, 11 which conform to the exterior periphery of the holder. The clip and its arms clasp the holder with sufficient friction to hold the device in position on the holder, and yet 90
allow for sliding movement of the clip when ejecting a cigarette butt and when loading the holder. 95

In Figure 2 it will be noted that the head 6 and the arm 8 are disposed on diverging lines from the bend 7, which positions are assumed by these parts when they are freed from a cigarette after ejection and from the inner wall of the socket head. To load the holder with the device in the position of Figure 2, the cigarette is forced over the head 6 in order that the head will pass into

the cigarette along the longitudinal center at its end. Then the clip and cigarette are moved together as one, the clip sliding back on the holder, the arm 8 sliding back into engagement with the inner wall of the socket head, and the inner end of the cigarette passing into and being anchored within the socket head, as in Figure 1. In this latter position the cigarette is positively retained within its holder for the smoker's use until the cigarette is consumed. For ejecting the cigarette butt the clip is slid along the holder from position of Figure 1 to the position of Figure 2, to remove the inner end of the butt from the socket head, after which the butt may be shaken from the device or tapped therefrom.

The clip, its head and arms, as before stated are of resilient material, such as metal, 20 and will readily adapt themselves to any slight variations in size or form of the conventional cigarette holders, and of course, if necessary the device may be made in different sizes to adapt it for different sizes of 25 holders.

In the form of the invention illustrated in Figures 4, 5 and 6 the same principles of invention are utilized for retaining and ejecting, and in addition means are provided for 30 cleansing the smoke duct 3 of the holder. The device of this modified form is also preferably of a single piece of resilient metal and the head 12 for insertion in the cigarette is fashioned of a double thickness, compactly 35 arranged to occupy a minimum of space in the inner end of the cigarette C. At the rear of the head a bend 13 is provided and the arm 14 which extends forwardly from this bend terminates in another bend 15 that 40 connects or joins the retainer with the sliding clip 16 which clip is fashioned with a pair of oppositely extending, open arms 17. The arms of the clip clasp around the cigarette holder to retain the clip in adjusted 45 position and the head 12 of elastic or resilient metal with its arm 14, also resilient, forms a V-shaped retaining device for use within the socket head of the holder.

For cleansing the smoke duct 3 an integral 50 stem 18 is extended rearwardly from the head 12 and is located within the duct.

The stem is of such length as to extend throughout the length of the holder, as in Figure 5, and reciprocates with the clip when 55 the latter is slid on the exterior of the holder for loading the holder or ejecting a cigarette

butt therefrom, and in this reciprocating movement tends to clear the holder and prevent accumulation of any deposits in the smoke duct. For scraping the interior walls 60 of the smoke duct, the clip 16 may be rotated around the holder or oscillated on the holder to turn and twist the stem within the holder and in contact with the walls 65 of the smoke duct. In this manner any accumulated deposits may be scraped from the walls of the duct. To further cleanse the holder, the attachment may bodily be removed from the holder and the latter then washed in any suitable manner for a 70 thorough cleansing.

While I have illustrated the clip and its arms as circular, it will be apparent that other forms may be adopted to adapt the 75 clip for use with holders of different peripheral formations. These and other similar changes I contemplate in the physical embodiment of my invention and may be made without departing from the spirit of 80 my invention.

Having thus fully described my invention, what I claim as new and desire to secure by Letters Patent is—

1. In a device as described the combination 85 of a slideable clip having a front bend and an inwardly extending arm of resilient material, a rear bend to said arm; and a head of resilient material projecting beyond said arm and adapted to receive a cigarette.

2. In a device as described the combination 90 of a slideable clip having an inwardly extending arm and an integral forwardly projecting head adapted to receive and retain a cigarette; and a stem extending rearwardly from said head.

3. In a device as described the combination 95 of a slideable clip comprising opposed resilient clasping-arms, a resilient arm on the clip extending within the clasping-arms, and a resilient head integral with and projecting beyond the front end of the arm to 100 receive and retain a cigarette.

4. The combination with a tubular holder having a socket head, of a longitudinally 105 slideable clip having a resilient V-shape formation comprising an arm adapted to frictionally engage the inner wall of the socket head and a forwardly projecting head to receive a cigarette or cigar.

In testimony whereof I affix my signature.

DOUGLAS COLLINS.
